UNITED STATES PATENT OFFICE.

HARRY C. GOODRICH, OF CHICAGO, ILLINOIS.

BLOTTER-SUPPORT.

SPECIFICATION forming part of Letters Patent No. 341,804, dated May 11, 1886.

Application filed March 15, 1886. Serial No. 195,220. (No model.)

To all whom it may concern:

Be it known that I, HARRY C. GOODRICH, of Chicago, in the county of Cook and State of Illinois, have invented certain Improvements in Blotter-Supports, of which the following is a specification.

The aim of my invention is to provide a simple and inexpensive means for holding blotters, pencils, and other articles commonly used by penmen, in such position that they may be instantly brought into use and instantly returned up to their normal position on being released.

To this end it consists, essentially, in an elastic standard having sufficient strength to sustain the blotter or other article, the standard being provided at one end with a screw connecting it with the desk or table, and provided at the opposite end with a clasp, or otherwise adapted to hold the blotter or its equivalent.

Figure 1 represents a perspective view of my device in its normal position. Fig. 2 is a similar view showing the action of the device 25 when the blotter is in use.

A represents a standard, constructed commonly of a single piece of steel wire or equivalent material. At its lower end the standard is fashioned into a horizontal eye, *a*, through 30 which a screw may be passed to secure it in an upright position on the top of the desk or other support. A washer, *b*, is commonly placed beneath the standard and attached thereto, or made separate therefrom, as preferred. At its upper end the standard is provided with an eye, *c*, to which there is connected the cord *d*, bearing at its opposite end an elastic U-shaped clasp adapted to embrace the edge of the blotter-sheet. The form of this 35 clasp may be modified according to the nature of the article which it is to hold.

In making use of the device it is secured, as shown, in an upright position at a distance from the front edge of the desk, and in such position that when erected will cause no inconvenience. When free, the standard remains in its upright position, suspending the blotter in view and in position to be conveniently reached.

When the blotter is to be used, it is drawn 50 forward and manipulated in the ordinary manner, the flexibility of the standard allowing it to yield, so that the blotter may be moved freely in all directions without being disconnected therefrom. When the blotter is released, the standard and blotter will resume 55 their original position.

It is obvious that the two ends of the standard may be modified in form, provided only that they are adapted for connection, respectively, with the desk or other support, and with the article to be sustained.

Having thus described my invention, what I claim is—

1. A support for blotters, pencils, and the like, consisting of a flexible arm provided with means of support or attachment at one end, and provided at the opposite end with means for the attachment of the blotter or its equivalent thereto.

2. A support for blotters, pencils, and the like, consisting of a flexible arm provided at one end with means of support or attachment, and at the opposite end with a cord having a clasp at its free end.

In testimony whereof I hereunto set my hand, this 1st day of March, 1886, in the presence of two attesting witnesses.

HARRY C. GOODRICH.

Witnesses:

DANIEL W. BROWN,
FRANK L. GOODRICH.
